UNITED STATES PATENT OFFICE.

VINZENZ SABADELLO, OF ST. POLTEN, AUSTRIA, ASSIGNOR TO FRANZ BENEDIKT, OF ST. POLTEN, AUSTRIA.

DEVICE FOR SECURING BUTTONS OR THE LIKE TO FABRICS OR ANY OTHER KIND OF MATERIAL.

Application filed November 5, 1923. Serial No. 672,883.

To all whom it may concern:

Be it known that I, VINZENZ SABADELLO, a citizen of the Republic of Austria, residing at 34 Schulpromenade, St. Polten, Austria, have invented certain new and useful Improvements in a Device for Securing Buttons or the like to Fabrics or Any Other Kind of Material, of which the following is a specification.

10 This invention relates to a device for securing buttons or the like without sewing to fabrics or any other kind of material and has for its principal object to provide a device which may be easily and quickly attached to any garment or the like.

An important object of the invention is to provide a device of this nature which will eliminate the necessity of providing button holes in the garment, or which can 20 be readily attached thereto in case the button is pulled off the garment.

With the above and numerous other objects in view as will appear as the description progresses, the invention resides in 25 certain novel features of construction, and in the combination and arrangement of parts as will be hereinafter more fully described and claimed.

One mode of carrying out the present invention is shown, by way of example, on 30 an enlarged scale in the accompanying drawing.

Fig. 1 illustrates a sectional view of the device, the section being taken on line *a*—*b* 35 of Fig. 2, and

Fig. 2 shows the device in front view.

1 designates a U-shaped bracket provided 40 with a slot 3 through which a double armed lever 2 passes, the latter being pivotally secured to the bracket at 1' and the arms of the same being disposed at an obtuse angle. A button 6 is secured in any convenient manner to the end of the outer arm of the said lever, while the inner arm 2' of the 45 latter projects into the interior of the bracket and is adapted to cooperate with the free end of a U-shaped clamping spring 4 disposed within the bracket 1. The latter is furnished with a recess 8 into which 50 extends and is secured a projection 7 stamped out of the one arm of the spring 4. Projections 5 facing one another are

stamped out of the metal of both arms of the clamping spring 4.

In order to secure the device to a fabric 55 or the like, the double armed lever 2, 2' and the spring 4 take up the position shown in dash-dotted lines in Fig. 1, and the device is pushed over the fabric in such a manner, that the latter rests between the 60 arms of the clamping spring 4 and now the outer arm of the lever 2 is swung upwardly so that the same takes up a position within the slot 3 of the bracket 1 substantially parallel to the slotted arm of 65 the said bracket, while the inner arm 2' of the lever will force the free arm of the spring 4 inwardly and take up the inclined position shown in Fig. 1 and the projections 5 will partly penetrate into the fabric 70 without damaging the same. Owing to the arrangement of the lever-arms at an obtuse angle and the resulting inclined position of the lever-arm 2' in the operative 75 position of the lever, the latter cannot be moved into the inoperative position by the force of the inwardly pressed arm of the spring 4, and thus the device is securely fastened to the fabric.

I claim:—

1. A device for securing buttons or the like to fabrics or any other kind of material comprising in combination, a bracket furnished with a slot at one of its arms, a clamping spring disposed within the said bracket, a double armed lever the arms of which are disposed at an obtuse angle pivoted to the said bracket in such a manner that in the operative position of the lever one of its arms rests within the said slot and the other arm thereof projects into the interior of the bracket and takes up an inclined position with respect to the slotted arm of the said bracket and cooperates with and forces inwardly one arm of the said 90 clamping spring, and a button secured to the lever-arm first mentioned.

2. A device for securing buttons or the like to fabrics or any other kind of material comprising in combination, a bracket furnished with a slot at one of its arms and with a recess at the other arm thereof, a clamping spring disposed within the said bracket the said clamping spring being fur- 100

nished with a projection which extends into the said recess, a double armed lever the arms of which are disposed at an obtuse angle pivoted to the said bracket in such a 5 manner that in the operative position of the lever one of its arms rests within the said slot and the other arm thereof projects into the interior of the bracket and takes up an inclined position with respect to the 10 slotted arm of the said bracket and coop-

erates with and forces inwardly one arm of the said clamping spring, and a button secured to the lever-arm first mentioned.

In testimony whereof I affix my signature in presence of two witnesses.

VINZENZ SABADELLO.
